Specification for Design.

Patented July 25, 1922.

Application filed March 2, 1922. Serial No. 992. Term of patent 7 years.

To all whom it may concern:

Be it known that I, EDMOND GAUDIOZ, a citizen of the Republic of France, residing at Watford, county of Hertfordshire, England, have invented a new, original, and ornamental Design for Textile Fabric, Wall Paper, Wrapping Paper, or Article of Similar Nature, of which the following is a specification, reference being had to the accompanying drawing, forming part thereof.

The figure is a plan view of a portion of a printed fabric showing an embodiment of my new design.

I claim—

The ornamental design for textile fabric, wall paper, wrapping paper, or article of similar nature, substantially as shown and described.

EDMOND GAUDIOZ.
